UNITED STATES PATENT OFFICE.

WILLIAM MILTON BROWN, OF JOHNSTOWN, PENNSYLVANIA, ASSIGNOR TO
LORAIN STEEL COMPANY, A CORPORATION OF PENNSYLVANIA.

ELECTRIC RAILWAY.

SPECIFICATION forming part of Letters Patent No. 730,869, dated June 16, 1903.

Application filed July 29, 1902. Serial No. 117,509. (No model.)

To all whom it may concern:

Be it known that I, WILLIAM MILTON BROWN, of Johnstown, in the county of Cambria and State of Pennsylvania, have invented a new 5 and useful Improvement in Electric Railways, of which the following is a full, clear, and exact description, reference being had to the accompanying drawings, which form a part of this specification.

10 This invention has relation to electric railways and is applicable to that class of electric railways known as "surface-contact systems," in which the propelling-motors receive their supply-current from an underground 15 feeder or conductor through surface contacts placed in the road-bed and normally disconnected from said feeder or conductor, but arranged to be temporarily connected therewith by means of the action of a magnet or magnets carried by the cars or vehicles. In this manner each of the surface contacts is energized or "alive" at such times only as a car 20 or vehicle is passing over it, and it is then engaged by a current-collecting shoe or trolley 25 on the car, from which the current is conveyed to the propelling motor or motors and from thence to the opposite side of the circuit, which may consist of the track-rails or any other suitable return-conductor.

30 In the practical operation of systems of this character it not infrequently happens that the car-magnet (which is kept constantly energized while the car is in motion either by a battery-current or by current derived from 35 the collecting-shoe or trolley or by a combination of both) will attract to itself pieces of scrap iron or steel, such as are not uncommonly present from various causes in the streets of cities and towns, and will hold such 40 pieces in position to enable them to make contact either with a surface contact or with the current-collecting shoe or trolley. The effect of this is that when the car passes over the rails of an intersecting or branching track 45 such piece of iron may make contact with a rail or rails of such track and also with a contact or with the shoe or trolley in such a manner as to form a short circuit for a portion of the feeder system. Such a short circuit results in an abnormal flow of current, which 50 may release the current-breaker or other pro-

tective apparatus at the supply-station, and thereby temporarily stop the supply to that portion of the line supplied by said station, or it may cause injury to the apparatus on 55 the line.

This invention is designed to obviate these results, and it consists in placing all those contact devices of the system which happen to be located adjacent to the rails of intersecting or branching tracks upon separate subfeeders, the ohmic resistance of which is so proportioned that they will carry sufficient current to propel the cars over and by the intersecting or branching tracks, but not 65 sufficient to cause a disturbance of the system should a short circuit occur in the manner above described.

The accompanying drawing shows diagrammatically the application of my invention to 70 a portion of a surface-contact system of the character above described in which is located a branch track.

In the drawing the main-track rails are designated by the letters *a* and the branch-track 75 rails by the letters *b*. The main supply-feeder *c* is led through a junction-box *d*, wherein connection is made with the subfeeders *e*, *f*, and *g*. Those contacts *h* of the main track which are not adjacent to the rails 80 of the branch track are supplied with current in series by the subfeeder *e* in the usual manner, and those contacts *i* of the branch track which are not adjacent to the rails of the main track are supplied with current by the 85 subfeeder *f*; but in accordance with this invention those contacts *j* on each track which are respectively adjacent to rails of the other track are placed on the short separate subfeeder *g* or upon branches thereof, and connected in series in this subfeeder is a suitable 90 resistance *k*. The ohmic value of this resistance *k* will preferably depend upon the local conditions. For instance, if the crossing is substantially level or is on a downgrade this 95 resistance may be made great enough so that only sufficient current will flow in the subfeeder *g* to keep the car-magnet excited and the lights of the car lighted, and the car can be allowed to "drift" over the crossing. If for 100 any reason the car should come to a stop while over this subfeeder, there will still be enough

current to move the car slowly if the motorman keeps the magnet excited by means of the battery-current with which the car is supplied. A current of twenty or thirty amperes (varying 5 perhaps from these limits under different conditions of track and load) would ordinarily be sufficient at such crossings, and if a short circuit should occur in the manner above described no harm would result. For crossings 10 where the grade is such that the car must always be driven without drifting the resistance may be adjusted to give, say, one hundred amperes or more of current in the sub-feeder. Inasmuch as the circuit-breaker at 15 the station is usually set as high as two hundred and fifty amperes, it will not be affected by the short-circuiting of this one-hundred-ampere current should it occur. These resistances are only illustrative; but in all 20 cases the resistance k should be so proportioned as to give sufficient current to enable the cars to be moved over the crossing, taking into consideration the conditions existent at such crossing.

25 The drawing illustrates but one condition—to wit, a branch track leaving a main track; but wherever on the system one or more tracks leave or intersect another track or tracks the contacts adjacent to the meeting 30 or intersecting rails should, in accordance with this invention, be placed on a separate subfeeder of sufficient resistance to effect the objects of the invention. The same thing

should also be done wherever any other metallic object along or adjacent to the system 35 might otherwise act in the same manner as a meeting or crossing track-rail.

Having thus described my invention, what I claim as new, and desire to secure by Letters Patent, is—

1. In an electric - railway system of the class described, the combination with surface contacts arranged adjacent to a rail or rails of a meeting or intersecting track, of a sub-feeder for supplying current to said contacts 45 and having an abnormally high resistance.

2. In an electric - railway system of the class described, means for preventing the disturbing effects of short circuits due to temporary connections which may be made by a car 50 between one or more of the surface contacts and an adjacent object, such means consisting of a subfeeder to which the contact or contacts adjacent to such object are connected, and which has its ohmic resistance 55 so proportioned as to supply the said contacts with sufficient current to enable the car to be moved past said objects, but not sufficient to disturb the system should such current be short-circuited.

In testimony whereof I have affixed my signature in presence of two witnesses.

WILLIAM MILTON BROWN.
